VACUUM TUBE

Vladimir K. Zworykin, Swissvale, Pa., assignor
to Westinghouse Electric & Manufacturing
Company, a corporation of Pennsylvania

Application November 16, 1929, Serial No. 407,652

6 Claims. (Cl. 250—27.5)

My invention relates to vacuum tubes and it has particular relation to devices of the type known in the art as cathode-ray tubes.

Cathode-ray tubes have been utilized for many years for the measurement or the indication of electrical power, the wave-form of alternating currents or potentials, or similar conditions in electric circuits. They have also been proposed for use in television systems, as indicated by the patent to Rosing 1,161,734. By reason of the fact, however, that it was substantially impossible to focus the cathode-ray to a well defined spot on the fluorescent screen, while still maintaining proper control of the intensity of the ray, such tubes have not, heretofore, been satisfactory as view-receiving devices.

It is, accordingly, an object of my invention to provide an improved cathode-ray tube.

Another object of my invention is to provide a cathode-ray tube capable of operating under accelerating potentials of the order of thousands of volts.

Another object of my invention is to provide a cathode-ray tube of the high-vacuum type so constructed as to not require continuous pumping while in use.

Another object of my invention is to provide a cathode-ray tube in which the electrodes are simple in construction and have small total volume, whereby their degasification, by well known processes, during evacuation of the device, is facilitated.

Another object of my invention is to provide a cathode-ray tube wherein the focusing of the ray is totally unaffected by the control-potentials.

Another object of my invention is to provide a cathode-ray tube wherein the ray may be focused to a well defined spot.

Another object of my invention is to provide a cathode-ray tube wherein the ray is equally well defined at all points to which it is deflected upon the fluorescent screen.

Another object of my invention is to provide a cathode-ray tube wherein the accelerating potentials may be made so large in respect to the intensity-control potentials that the deflection of the ray is not influenced by the said control potentials and is the same for all intensities.

A further object of my invention is to provide a cathode-ray tube wherein the electrons are accelerated in two stages, one stage at a low potential and another stage at a high potential, and wherein deflection of the electrons is accomplished between the said stages.

Still another object of my invention is to pro-

vide a cathode-ray tube having such characteristics as will render it especially useful in view-transmission systems.

Specifically, a cathode-ray tube, comprising a preferred embodiment of my invention, includes an electron gun constituted by a thermionic cathode, a control-electrode and a primary anode, and it also includes a conductive coating, a portion of which is fluorescent, upon the interior of the large end of the tube to constitute a secondary or accelerating anode. 5

I apply a very high potential between the primary and secondary anodes, and the converging electrostatic field, set up thereby, causes the cathode-ray to be focused to a well defined spot 10 upon the fluorescent screen.

The novel features that I consider characteristic of my invention are set forth with particularity in the appended claims. The invention itself, however, both as to its organization and 20 its method of operation, together with additional objects and advantages thereof, will best be understood from the following description of a specific embodiment, when read in connection with the accompanying drawing, in which:

Figure 1 is a diagrammatic sectional view of a cathode-ray tube comprising a preferred embodiment of my invention, and

Fig. 2 is an enlarged detail view, partly in cross-section, showing the construction of the 30 electron-gun.

The tube illustrated in the drawing comprises an elongated container 1 having a pear-shape end 2. One end of the container is provided with a reentrant press 3 through which a plurality of lead-in elements 4, 5 and 6 extend and which carries a clamping device or collar 7. A plurality of rigid rods 8 extend inwardly from the collar and carry an anode 10 constituted by a cylindrical wall portion 11 and two circular end walls 12. A thermionic cathode 13 is carried by the inner ends of the lead-in elements 4 and is disposed closely adjacent to an opening 15, approximately 100 mils in diameter, in the bottom wall of a cup-shape control-electrode 16 that is supported from the lead-in element 5 and another similar element 17 mounted on the press. Each of the end walls 12 of the anode 10 is provided with a small opening 18 having a diameter of approximately 60 mils, the said openings 50 and the opening 15 in the control-electrode being coaxial. 45

The cathode is surrounded by a cup-shape shield 19. The shield is carried by one of the lead-in elements 4 that support the cathode and 55

is, consequently, maintained substantially at cathode-potential. The edge of the shield is closely adjacent to the bottom of the cup-shape control-electrode 16 and, by preventing scattering of the electrons, increases the efficiency of the said electrode.

One of the supports 8 of the anode 10 is provided with an extension 20 having a cupped end portion 21 adapted to carry a small amount of getter material, such as magnesium, which is flashed during the evacuation process.

The cathode, although illustrated as being a filament, may be of the equipotential type, if desired, or of any other type capable of giving sufficient electron emission.

A metallic deposit 22 covers the entire inner surface of the wall of the pear-shape portion 2 of the container and constitutes an accelerating, or focusing, anode. The deposit on the extreme 20 rounded end of the tube is sufficiently thin to be translucent and over it is applied a coating 23 of fluorescent material, such as finely divided willemite, to constitute a ray-receiving screen.

As an alternative, the metallic deposit, upon the 25 inner surface of the extreme end of the vessel, may be omitted, in which event a conductive material, such as finely divided silver, is mixed with the fluorescent material before it is placed in the tube. If the screen is of the type comprising 30 conductive material, instead of being deposited upon a conductive surface, it is highly important that the said material be connected to the accelerating-anode 22. The connection between the screen and the accelerating anode is for the 35 purpose of carrying away the charge conveyed to it by the cathode-ray, since an accumulated charge prevents focusing of the ray to a well defined spot.

The exact manner in which the metallic coating 40 is applied is not important although I have found it expedient to deposit it from a solution of alkaline silver nitrate, in the manner well known to those skilled in the chemical arts.

A plurality of ray-deflecting devices 24 and 25 45 are disposed exteriorly of the vessel, intermediate the primary anode and the inner edge of the metallic deposit 22, whereby the cathode-ray may be caused to move over the fluorescent screen in any path desired.

In the operation of my improved cathode-ray tube, as a view-receiving device in a television system or the like, the first anode 10 is maintained at a positive potential of approximately 300 volts with respect to the cathode, and the 50 metallic coating 22, on the inner wall of the tube, which constitutes the accelerating anode, is maintained at a positive potential of approximately 3,000 volts with respect thereto. The relation between the anode voltage and the voltage applied 55 to the metallic coating is critical and I have found that, for best results, with a tube wherein the distance between the cathode and the screen 23 is approximately 20 inches, and the distance between the extreme end of the anode 10 and the 60 edge of the metallic deposit nearest thereto is about two inches, the potential of the coating should be approximately 10 times that of the anode.

When a negative potential of about 30 volts is 65 applied to the control-electrode 16, the cathode ray is entirely blocked; potentials less negative cause variations in the intensity of the ray proportional thereto, with corresponding variations in the brilliancy of the fluorescence of the spot 70 on the screen.

The relatively low potential required for control of the intensity of the electron stream is an important feature of my invention. It follows from the relative positioning of the cathode, the control-electrode and the anode, the dimensions 5 of the coaxial openings therein, and the complete enclosure of the cathode by the said control-electrode, that the number of electrons, rather than their velocity, is controlled. Since the control-potential need be only a very small fraction of 10 the accelerating potential between the anode and the coating 22, the electron stream is not appreciably retarded thereby, and the deflection of the stream, by the devices 24 and 25, is independent 15 of its intensity.

The control-electrode, therefore, may be utilized to impress view-frequencies upon the device, as disclosed in my copending application, Serial No. 349,956, filed March 26th and assigned to the Westinghouse Electric & Manufacturing Company, while the scanning-frequencies may be impressed upon the ray-deflecting devices 24 and 25, in the manner disclosed in the same application. The tube, however, is not to be considered as limited to use in television systems, since 20 it is also useful in electro-cardiographs, oscilloscopes and the like.

Under certain conditions, particularly if there is a possibility that the ray may remain on one spot for an appreciable time, it is advisable to 30 apply a cooling medium to the exterior of the screen. For this purpose, a transparent water-jacket may be utilized or a small fan may be mounted adjacent to the device.

In a view-receiving device, it is necessary that 35 the fluorescent spot shall be well defined and shall have a definite diameter in order to cover properly the distance between two adjacent scanning lines on the screen. By research and experiment, I have determined that such a spot can be secured by 40 proper choice of the size of the opening in the first anode and by the proper relation between the first and second potentials.

I am not, at this time, prepared to state exactly how the high positive potential applied to 45 the metallic coating functions to assist in focusing the cathode-ray to a well defined spot. It is probable, however, that the focusing is aided by the interaction between the magnetic field set up by the moving electrons and the convergent electrostatic field through which they pass.

Furthermore, the provision of a conductive fluorescent screen connected to the accelerating anode is an important feature of my improved cathode-ray tube, since the screen is thereby 55 prevented from acquiring a high negative charge that would tend to repel the cathode ray and cause blurring.

It also lies within the scope of my invention to mix with the fluorescent substance a small 60 amount of phosphorescent material or material that tends to glow for a short time after cessation of the electron impact. Such material, when incorporated into the screen, assists materially the phenomenon of "persistence of vision," permitting a decrease in the number of "frames" 65 transmitted and received per second when the tube is utilized for the distant reproduction of motion-picture films, as illustrated in my copending application hereinbefore referred to.

Although I have shown and described a specific embodiment of my invention, I am fully aware that many modifications of the structural details are possible. My invention, therefore, is not to be restricted, except insofar as is necessitated by 70 75

the prior art and by the spirit of the appended claims.

I claim as my invention:

1. A cathode-ray tube including an electron-source and a first anode, a fluorescent screen and means, including said screen and a second anode adapted to be maintained at a higher voltage relative to said source than said first anode for establishing a convergent electric field around the major portion of the path traversed by an electron between said source and said screen, whereby electrons from said source may be focused to a well defined spot on said screen.
2. A cathode-ray tube comprising an electron-source, a shield for said electron source, a control-electrode substantially enclosing said source and having a small opening in a wall thereof, a first anode having a small opening spaced from the opening in the control-electrode and in axial alignment therewith, and a second anode which is also a focusing device capable of being maintained at a high positive potential with respect to said cathode, whereby control may be had of an electron stream in said tube without appreciably decelerating it.
3. A cathode-ray tube comprising a container exhausted to a high vacuum, an electron-source, a shield for said electron source, a control-electrode, a first accelerating electrode and a second accelerating electrode within said container, the last named electrode being constituted by a conductive deposit upon the inner surface of the said container.
4. Electron apparatus comprising an evacuated envelope, a viewing screen at one end of the envelope, means disposed at the other end of said envelope for developing a ray of electrons and directing the same toward said screen, said means

comprising a cathode, a shield for said cathode, and an anode and a control electrode interposed therebetween, said electrode being in the form of an apertured shield effective to prevent travel of electrons from said cathode to said anode along paths around said electrode, and single anode means disposed between said screen and said first-named anode and electrically disconnected and insulated from the latter to hold a potential greater than that on said first-named anode by thousands of volts, said anode means being constructed and disposed to develop an electrostatic field effective to focus said ray on said screen.

5. An electron tube having a coating of electrically conductive material on the interior surface 15 of the side wall thereof, said tube provided on an end wall thereof with an interior coating characterized by the fact that the same is fluorescent and electrically conductive and translucent, the adjacent edge portions of said coatings overlapping, and means for scanning the fluorescent coating.

10 6. A cathode ray tube including an electron source, a shield for said electron source, a first anode, a control electrode positioned in register 25 and between said electron source and first anode, a fluorescent screen and means, including said screen and a second electrode adapted to be maintained at a higher voltage relative to said source than said first anode for establishing a 30 convergent electric field around the major portion of the path traversed by an electron between said source and said screen, whereby electrons from said source may be focused to a well defined spot on said screen substantially independent of 35 the potential of said control electrode.

VLADIMIR K. ZWORYKIN.
